UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

SEWING-MACHINE THREAD PULL-OFF.

1,082,636.

Specification of Letters Patent.

Patented Dec. 30, 1913.

Application filed January 14, 1910. Serial No. 538,086.

To all whom it may concern:

Be it known that I, ALBERT E. JOHNSON, a citizen of the United States, residing at Beverly, in the county of Essex and State of 5 Massachusetts, have invented certain new and useful Improvements in Sewing-Machine Thread Pull-Offs; and I do hereby declare the following to be a full, clear, and exact description of the invention, such as 10 will enable others skilled in the art to which it appertains to make and use the same.

This invention relates to attachments for 15 sewing machines designed to provide for a sufficient free end of thread at the working point, after the removal of one piece of work, for use in the formation of the first stitch in the new work to be operated upon.

The invention relates more particularly to 20 an attachment for the purpose described which instead of operating on the tension device, as is common, operates directly on the thread to pull it through the tension. The attachment may, therefore, conveniently be termed a "thread pull-off."

25 It is desirable, in devices of this character, that the slack thread for use in forming the first stitch in new work be provided before removal of the old work from the machine so that when the old work is removed the 30 desired length of thread may be drawn freely through the guides and eye of the needle.

One object of the present invention, therefore, is to insure the provision of slack 35 thread, for use in the formation of the first stitch in new work, prior to the removal of the old work from the machine.

In accordance with this object, one feature 40 of the invention comprises a mechanically operated thread pull-off constructed and arranged to operate in advance of the removal of the work which has just been completed. To insure such an operation of the thread pull-off it may conveniently be connected to 45 the devices for lifting the presser foot from the work so that when the presser foot is lifted slack thread will be drawn through the tension device.

It is obvious that the strain placed upon 50 the thread by the pull-off should be removed prior to the removal of the old work so that no hindrance to the ready passage of the slack thread through the guides will be interposed.

55 Another object of the invention is to pro-

vide a thread pull-off which, after having performed its work to obtain the desired amount of slack thread, will be actuated to remove pressure from the bight of thread which it has formed.

In accordance with this object a further feature of the invention consists in the construction and arrangement of the thread pull-off in which a thread pulling finger acts upon the thread to draw slack through 65 the tension device and is then automatically returned to its normal, operative position prior to the removal of the old work.

In the illustrated embodiment of the invention an oscillatory thread pulling finger, 70 having a thread engaging end, is provided at the forward side of the tension device and this finger is oscillated to pull thread through the tension device by means of an actuator connected with the devices controlled by the operative for lifting the presser foot preparatory to removing the work. Means is provided for breaking the connection between the finger and its actuator after the desired length of thread has been pulled 80 off and a spring then returns the finger to its normal, operative position. The thread pulling finger is thus actuated to form slack thread by means under control of the operative but is automatically returned to its 85 normal, operative position. A variation in the length of thread pulled off is obtained by a variation in the effective length of the oscillatory thread pulling finger.

A thread pull-off of the character described provides for the withdrawal of a definite amount of thread from the spool, the thread pulling finger being preliminarily adjusted by the operative thus pre-determining the amount in accordance with 95 the length of thread necessary in stitching through any particular piece of work being operated upon. By this means a waste of thread is prevented.

Other features of the invention, comprising certain details of construction and combinations of parts, will be further explained in the following description and then pointed out in the appended claims.

In the drawings, which illustrate the best 105 form of the invention now known to the inventor, the thread pull-off has been shown as applied to the well known Willcox & Gibbs domestic sewing machine although it should be distinctly understood that the in-

vention is not limited in its application to that or to any particular type of sewing machine.

In the drawings Figure 1 is an elevation of the front of the machine; Fig. 2 is an elevation, in detail, of the parts of the thread puller at the rear of the machine; Fig. 3 is a plan of the parts shown in Fig. 2; and Figs. 4 and 5 are detached details, in perspective, to be referred to.

In the illustrated embodiment of the invention the domestic or household Willcox & Gibbs sewing machine head, except for certain modifications referred to later, is mounted on a base 1 and is provided with the usual stitch forming mechanism including the eye-pointed needle 2 and rotary thread hook or cast-off 3; the latter being mounted at one end of the driving shaft 4 rotated by a belt running over the sheave 5. The needle is actuated in the usual manner. The work is fed over the table 6 by the feed foot 7 actuated in the usual manner. The work is held upon the table 6 during the formation of the stitches by the presser foot 8 having the usual connections. The thread 9 leads from the spool or bobbin (not shown) through a usual form of tension device 10, and through the ordinary guides, to the eye of the needle.

The head, as illustrated, is modified from the commercial machine to the extent that the work table is smaller, the feed foot is thinner, and an additional work supporting roll 11 is provided mounted on a pivoted lever 12, and held in a position opposite the edge of the work table by a coiled spring 13. These changes are for the purpose of adapting the machine to sewing together the two flaps of an Economy insole to form a single, compound lip. As the changes form no part of the present invention, being claimed in a co-pending application of even date herewith Serial No. 538,087, they will not be referred to further herein.

The presser foot 8 is provided with a shoulder 14 (dotted lines Fig. 1) which is engaged by the left hand end of a lever 15 of the first class, fulcrumed on a stud 16 in a bracket carried by the frame (Fig. 1). The lever 15 is adjustably connected, by its right hand end, to a lever 17 of the second class, also fulcrumed on the stud 16, and is actuated by said lever 17. A chain 18 depends from the free end of the lever 17 and has connected thereto a treadle of usual form (not shown).

Rising from the lever 17 and pivotally mounted thereon by its lower end is an arm 60 or actuator 19 having a hooked end 20. A leaf spring 21 mounted on a bracket 22, which embraces the arm 19 and acts as a guide therefor, holds said arm in contact with a rotary cam-shaped member 23 (Fig. 4) pinned to one end of a rock shaft 24

journaled in the upper portion of the frame. The rotary member 23 is provided with a slabbed-off side 25 ending in a hook or spur 26 and, substantially diametrically opposite the spur, with a shoulder 27. The rotary member 23 is normally maintained with its shoulder 27 in engagement with a stop screw 28 by means of a suitably connected coiled spring 29 (Fig. 3) surrounding the shaft 24. The end of the shaft 24, opposite to that on which the member 23 is mounted, is split (Fig. 1) and drilled diametrically for the reception of the shank of a thread pulling finger 30 which is clamped in place by tightening a screw 31 in the shaft. The finger 30 extends forward and is provided at its free end with an eye 32 (Fig. 5) adjacent the tension device through which the thread freely passes after it leaves the tension. The coiled spring 29 maintains the finger 30 normally in its operative position as shown in Fig. 1.

In the operation of the machine, after the stitching on any particular piece of work has been completed, the free end of the lever 17 is drawn down by operating the treadle attached to the chain 18 and the presser foot 8 is thus lifted from the work by the engagement of the upwardly moving end of the lever 15 with the presser foot shoulder 14. The downward movement of the lever 17 carries down with it the arm 19 causing its hooked end 20 to engage the spur 26 on the rotary member 23 and rock the shaft 24. The rocking of the shaft 24 continues until the upper end of the slabbed off portion 25 of the rotary member engages the hook 20 (see dotted lines Fig. 2) and, acting as a tappet cam, pushes the hook off of the spur. The rocking of the shaft 24 has, however, brought the thread pulling finger to the lower dotted line position of Fig. 2 pulling thread through the tension and forming a bight of the desired size in the thread, as shown in dotted lines. Immediately the arm 19 is disengaged from the rotary member 23 the coiled spring 29 acts to rock the shaft 24 backward and bring the finger 30 to its normal, operative position thus relieving the thread of pressure from the finger. With this construction the finger is automatically returned to its initial position while the presser foot is held lifted and by means independent of the means for operating it. With the finger in its initial position and the presser foot still held lifted, the work may be removed and the slack thread readily drawn taut through the finger, guides and eye of the needle. At the time the thread is severed the free end of thread thus obtained has been drawn through the eye of the needle to a position ready for use in the formation of the first stitch in the new work.

The amount of thread pulled from the spool and the size of the bight formed by

the finger 30 can readily be varied, to suit any special condition by an adjustment of the finger on the shaft 24. This will vary the effective length of the finger and slack 5 thread will be obtained in proportion.

The nature and scope of the present invention having been indicated and its preferred embodiment having been specifically described, what is claimed as new, is:—

10 1. A sewing machine, having, in combination, stitch forming mechanism, a tension device, a presser foot, means to lift the presser foot, a thread pulling finger, operative connections from the presser foot lifting means to move the finger in a direction to pull thread through the tension device, and a device for returning the finger to its initial position acting independently of the movement of the presser foot lifting means.

15 2. A sewing machine, having, in combination, stitch forming mechanism, a tension device, a thread pulling finger, a presser foot, means to lift the presser foot and actuate the finger to pull thread through the tension device, and means to return the finger to its normal, operative position while the presser foot is held lifted.

30 3. A sewing machine having, in combination, stitch forming mechanism, a tension device, a rock shaft having a thread-engaging member mounted thereon, a cam member mounted upon said shaft, an arm in operative engagement with said cam member, means to actuate the arm and move the 35 rock shaft to cause the thread-engaging

member to pull slack thread from the tension device, and means to return the rock shaft and thread-engaging member to their initial position.

4. A sewing machine, having, in combination, stitch forming mechanism, a tension device, a rock shaft having a thread engaging finger, a cam member having a spur mounted on said shaft, a hooked arm for engaging said spur, means to actuate the arm to rock the shaft and cause the finger to pull slack thread through the tension device, a shoulder on the cam member to engage the hooked arm during the rocking of the shaft and disengage it from the spur and means to return the shaft and finger to their initial positions.

5. A sewing machine having, in combination, stitch forming mechanism, a tension device, a rock shaft having a thread-engaging finger, a rotary cam member having a spur mounted on said shaft, a hooked arm for engaging said spur, means to actuate the arm to rock the shaft and cause the finger to pull slack thread through the tension device, a slabb'd-off portion terminating in a shoulder formed on the cam member to engage the hooked arm during the rocking of the shaft and disengage it from the spur, and means to return the shaft and finger to their initial positions.

ALBERT E. JOHNSON.
